UNITED STATES PATENT OFFICE.

ALBERT M. SKINNER, OF WATERTOWN, NEW YORK.

WALL PLUG.

Application filed December 7, 1926. Serial No. 153,171.

This invention relates to an improved nailing plug for use in any type of masonry construction. The wall plugs now in use are either set in place as the masonry is laid or are driven into holes drilled into a finished wall. Usually such plugs are merely retained by friction. Thus where the plug is laid up in the wall shrinkage of the plug may free it. In the case where a tapered plug is driven into a drilled hole either shrinkage or the splintering of brick or tile around the plug may result in eventual loosening of the plug.

The purpose of the present invention is to overcome the above difficulties, and this is accomplished by the use of a plug consisting of a core and a shell, the plug being preferably of wood and the shell preferably of metal. The plug and shell are permanently fixed to each other by interengaging projections and recesses, the plug offering a hold for nails and the shell effecting the engagement with the wall. Since the shell is of metal or other tough nonshrinking material, a permanent engagement with the wall is thus secured.

A practical embodiment of the invention is illustrated in the accompanying drawings, in which,—

Fig. 1 is a longitudinal axial section of a form of plug intended to be driven into a hole drilled in the wall.

Fig. 2 is a side elevation, partly in section, of the plug shown in Fig. 1, on a slightly enlarged scale.

Fig. 3 is a perspective view of the metal shell.

Fig. 4 is a sectional view, similar to Fig. 1, showing a modified form of plug which is laid in the joint of the wall as this is constructed.

Fig. 5 is a perspective view of the plug shown in Fig. 4, a portion of the shell being broken away.

Fig. 6 is a perspective view of another modified form of plug.

Referring first to Figs. 1 to 3 inclusive, the wall plug is shown as consisting of a wooden core 9 encased in a corrugated metal shell 10. Preferably the core is circumferentially ribbed to fit the corrugations on the shell and thus lock the shell and core

together. The plug of Fig. 1 may be formed by wrapping a strip of corrugated metal around a wooden plug, or it may be constructed by slipping a tubular sleeve over the plug and then rolling mating corrugations into the core and shell at the same time. The plug of the type shown in Figs. 1, 2 and 3, is intended to be driven into a drilled hole. While the corrugated shell will enter into frictional contact with the wall and by its resulting deformation will secure a strong grip, I prefer to make use of a cementing material 11, such as plaster of Paris. Plaster of Paris is preferred because of its property of expanding as it sets. A plug so set will never become loose, since the wooden core is locked into the metal shell and since the metal shell is permanently bonded to the wall. The insertion of nails and screws only increases the tightness of engagement of the plug to the wall.

In Figs. 4 and 5 there is illustrated another type of plug which is generally similar to that shown in Fig. 1 except that it is flattened and widened in order that it may be laid up in the masonry wall as the wall is constructed. Aside from the general configuration of the plug, it is essentially the same as that shown in Fig. 1.

Fig. 6 shows another modification in which the wooden core 9 is enclosed in a jacket 14 of tubular wire braid. This is a peculiarly good construction, because as the wire fabric is elongated it shrinks and seizes the core tightly and at the same time its outer surface is so rough as to offer good frictional contact with the wall and a very good surface for bonding with plaster and the like.

Various other modifications may be made within the scope of the present invention.

What is claimed is,—

1. As a new article of manufacture, a wall plug comprising a core adapted to receive nails, and a rough jacket adapted to enter into binding engagement with the wall, the exterior of the core and the interior of the jacket being provided with interengaging projections and recesses.

2. As a new article of manufacture, a wall plug comprising a corrugated wooden core and a corrugated metal jacket encasing

said core, the corrugations of the core and jacket interengaging with each other to fix the core within the jacket. 10

3. As a new article of manufacture, a wall plug comprising a core and a metal jacket encasing the same, the jacket being formed with projections and recesses on both its in-

terior and exterior faces, and the core and jacket being locked together by engagement of the core with such projections and recesses. 10

In testimony whereof I have signed my name to this specification.

ALBERT M. SKINNER.
